[57] CLAIM

The ornamental design for an evaporator casing for the heat exchanger of an air conditioner, as shown.

DESCRIPTION

FIG. 1 is a top, front, and left side perspective view of an evaporator casing for the heat exchanger of an air conditioner showing my new design;
FIG. 2 is a left side elevation view thereof, the opposite side being a mirror image of that shown;
FIG. 3 is a rear elevation view thereof;
FIG. 4 is a front elevation view thereof;
FIG. 5 is a top plan view thereof; and,
FIG. 6 is a bottom plan view thereof.

FIG. 1

FIG. 2

FIG. 3

FIG. 4

FIG. 5

FIG. 6
